UNITED STATES PATENT OFFICE

2,585,625

DOOR CHECK MECHANISM

Martin Carlson, Brookfield, Ill., assignor to
George W. Housby, Jr., Chicago, Ill.

Application January 21, 1950, Serial No. 139,831

2 Claims. (Cl. 16—55)

1

This invention relates to door check mechanisms, and more particularly to such mechanisms which are adapted to the control of the movements of single acting doors which move in only one direction from a closed position and close against a jamb.

It is a general object of my invention to provide an efficient and effective door check mechanism of the type adapted to mounting in substantially flush relationship to a surface at one end of a single acting door for normally holding the door closed and for controlling movements of the door to one side of that closed position.

My invention further has within its purview the provision of a door check mechanism of the type adapted to serve as a hinge or pivot for a door and which embodies an inexpensive, but effective seal for preventing the leakage of liquid or lubricant from the housing of the mechanism along the door spindle thereof.

As another object, this invention comprehends the provision of a door check mechanism which provides different rates of motion of a single acting door at different portions of the door closing movements and which is adapted to be readily and accurately adjusted for effecting relatively rapid door closure without noise, and to hold such an adjustment, so as to provide long and consistent service.

The invention has for another object the provision of a door check mechanism of the type referred to and in which the parts of the mechanism are so constructed and arranged that a single cam element serves to effect operation of the controlling parts of the mechanism and as an element for transmitting forces of the mechanism to the door.

Other objects and advantages of the invention will be apparent from the following description and the accompanying drawings in which similar characters of reference indicate similar parts throughout the several views.

Referring to the five sheets of drawings,

Fig. 1 is a top plan view of the exterior of a door check mechanism embodying a preferred form of my invention;

Fig. 2 is a side sectional view wherein outer casing parts and an inner housing for the mechanism are cut away substantially at the position indicated by a line 2—2 in Fig. 1, and with the internal mechanism viewed in elevation in the direction indicated by arrows;

Fig. 3 is a bottom sectional view wherein the section is taken substantially on a line 3—3 of Fig. 2 and viewed as depicted by the accompanying arrows;

2

Fig. 4 is a view similar to Fig. 2, but wherein the mechanism is viewed from the opposite side;

Fig. 5 is a fragmentary side sectional view wherein the section is taken substantially as indicated by a line 5—5 of Fig. 3 and accompanying arrows;

Fig. 6 is an end sectional view wherein the section is taken substantially on a line 6—6 of Fig. 4 and in the direction indicated by arrows;

Fig. 7 is a fragmentary side sectional view wherein the section is taken substantially on a line 7—7 of Fig. 8 and in the direction of the arrows;

Figs. 8 and 9 are end sectional views in which the sections are taken substantially as indicated by lines 8—8 and 9—9 in Fig. 7 and in the directions of the arrows; and

Figs. 10, 11 and 12 are similar top sectional views taken substantially at a position indicated by a line 10—10 of Fig. 2 and in the direction of the arrows; the three figures depicting different operating positions of the parts of my door check mechanism.

Considered generally, the exemplary door check mechanism which is depicted herein for illustrative purposes is adapted to mounting at one end of a door and to serve as a hinge upon which the door is mounted for swinging movement. The purpose of the mechanism is to bias the door to a closed position and to effect movement thereof to that closed position at a varying rate, so that the door is closed with relative rapidity but without slamming. Although parts of the mechanism might be adapted to a double acting door check mechanism, such as are utilized for doors which swing in two directions from a central position, the door check mechanism herein shown is suited to use on a single acting door which swings in only one direction from its closed position and is held closed against a jamb.

In the form illustrated, a door check operating mechanism 15 is secured to a cover plate 16 and movably mounted in an outer casing 17; the combination being adapted to mounting with the cover plate 16 in substantially flush relationship to the floor or sill below a door. A spindle 18 projects upwardly from the cover plate 16 and has a tapered end portion 19 which is adapted to fit snugly into a socket in the end of the door and to serve as a hinge upon which the door is mounted.

The mechanism generally is of a spring actuated and liquid controlled type. That is, within the operating mechanism, a cam 20 is secured to the spindle 18 within the casing and

serves to transmit door operating force to the spindle from relatively heavy compression springs 22 and 23. In addition to variations in the door operating force which are effected by differences in the leverage produced by the cam contour, the mechanism further embodies a control mechanism, shown generally in Fig. 5, which operates during the spring actuated portion of the door movement and by controlled liquid flow to provide adjustable variations in the door closing movement. The cam 20 on the spindle 18 which is acted upon by the compression springs 22 and 23 also serves as the actuating element of the control mechanism.

Considering my disclosed door operating mechanism and its operating parts and their relationships in greater detail, the cover plate 16 fits into the top of the outer casing 17 and rests against integral shoulders 24 (Figs. 6, 8 and 9) which extend along the sides of that casing; the cover plate being secured to the outer housing by fastening means, such as screws 25 (Fig. 1). An inner liquid tight housing 26 has a flanged top margin 27 and is secured in liquid tight relationship to the inner surface of the cover plate 16 by fastening means, such as screws 28. A liquid, such as oil, normally fills the inner housing 26 to a level 29 near the cover plate 16, as shown in Fig. 2, so that the operating parts of the mechanism 15 function in a liquid bath, and the inner housing serves as a sump or supply container for the liquid utilized in effecting regulated control of the door closing movement.

Within the inner housing, a cylinder block 30 is secured to the cover plate 16 and has therein, in side-by-side and adjacent relationship, a cylinder bore 32 and slide block bearing 33 (Figs. 5, 7 and 9); the axes of the cylinder bore and slide block bearing being substantially parallel to one another. Both the cylinder bore and the slide block bearing extend through the cylinder block and have ends opening toward the spindle end of the housing. Furthermore, the cylinder block 30 preferably has formed as an integral part thereof a projecting supporting flange portion 34 at the spindle end. As shown in Figs. 4, 5, 6 and 7, the supporting flange portion 34 of the cylinder block is in spaced and substantially parallel relationship to the cover plate 16.

With the parts thus arranged and disposed, anti-friction bearings 35 and 36 are utilized to support the spindle 18 for rotation relative to the cover plate 16 and supporting flange portion 34 respectively. An insert 37 having a collar portion 38 and an externally shouldered portion 39 fits into a bore 40 in the cover plate 16 and provides an outer race for the anti-friction bearing 35. The collar portion 38 of the insert has an internal groove 42 therein which carries a sealing washer 43 of substantially X-shaped section. This washer fits into the internal groove 42 and is made of a resilient material such as rubber, so that it engages the exterior of the spindle 18 to serve as a shaft seal. Additionally, the spindle provides an inner race 44 for the anti-friction bearing 35 and has internally of the housing from that race a shoulder 45 thereon which provides an annular seat for a flanged resilient washer 46. The latter washer being made of a resilient material such as rubber has its outer flanged edge biased into engagement with the margin of the internal surface of the insert 37 to provide an inner shaft seal. These seals not only prevent the liquid

from leaking out of the inner housing along the spindle, but also seal the anti-friction bearing to retain its lubricant. It may be observed that the arrangement of the inner and outer races for the anti-friction bearing 35 is such that that bearing is adapted to absorb axial thrust, as well as providing radial support for the spindle.

At the other end of the spindle, an inner race 47 for the anti-friction bearing 36 is formed thereon. An apertured disk 48 which is seated for axial movement in a counterbore 49 in the supporting portion 34 of the cylinder block provides an outer race 50 for the anti-friction bearing 36; the inner and outer races 47 and 50 being disposed to receive axial thrust from the spindle, as well as to provide radial support therefor. An apertured screw plug 52 is threaded into a bore 53 in the supporting portion 34 of the cylinder block in coaxial relationship to the disk 48 and serves as an adjustable seat for that disk by which the axial position of the outer race 50 may be adjusted to take up any end play of the spindle. The cam 20 may be made as an integral part of the spindle although it is preferably fabricated as a separate piece and drivingly secured to the spindle, and located axially of the spindle by a shoulder 54, as shown in Fig. 6.

As shown in Figs. 4, 7 and 9 to 12, the slide block bearing 33 in the cylinder block carries a slide block 55 for linear sliding movement in alignment with one side of the cam 20. At the end adjacent the cam, the slide block 55 is bifurcated to provide projecting fingers 56 and 57, which fingers have secured thereto a cross shaft 58. A roller 59 is supported for rotation by the cross shaft 58 between the fingers 56 and 57 and serves as a follower for engagement with a surface 60 of the cam 20.

At the end of the slide block 55 opposite the roller 59, bars 62 and 63 are seated in bores 64 and 65 and secured in place therein, so as to project from the slide block in substantially parallel relationship to one another. Flanged seating washers 66 and 67 are carried by the bars 62 and 63 adjacent the end of the slide block 55 to provide seats for one end of each of the compression springs 22 and 23 respectively.

At a distance from the slide block bearing 33 and in alignment with the bars 62 and 63, an abutment bracket 68 is secured to the cover plate 16 and has threaded bores 69 and 70 therethrough, which bores are coaxial with the bars 62 and 63 and have abutment elements 72 and 73 threaded therein for adjustment axially of the bars. The abutment elements 72 and 73 are provided with axial bearings 74 and 75 which receive the ends of the bars 62 and 63 to provide supports therefor. Flanged seating washers 76 and 77 abut the ends of the abutment elements 72 and 73 and receive the ends of the compression springs 22 and 23 opposite the slide block 55, whereby those compression springs are supported to exert a force upon the slide block and thence through the cam roller 59 to the cam 20. In the disclosed structure, the springs 22 and 23 and the bars 62 and 63 are disposed one above the other. Access for effecting adjustment of the positions of the abutment elements 72 and 73 relative to the abutment bracket 68, so as to adjust the pressure of the springs 22 and 23, is attained by removal of a screw plug 78 which is threaded into an opening 79 in the cover plate.

16. In order to provide ease of adjustment of the force of both of the springs 22 and 23 at one time and through the opening 79 in the cover plate, the abutment elements 72 and 73 are reversely threaded into their respective threaded bores 69 and 70, and those abutment elements are drivingly connected by gears 80 and 82 which are respectively secured thereto. Also, the abutment element 72 which is adjacent the opening 79 has secured thereto a peripherally perforated disk 83, the perforations in which disk serve as sockets for turning the abutment elements with a simple tool from the exterior of the housing.

A door mounted on the spindle 18 normally occupies a general plane such that the door surfaces are substantially aligned with the flattened side surfaces of the end portion 19 of the spindle. It being desirable in a single acting door check mechanism that the mechanism shall exert a force to hold the door against a jamb, it is preferable to allow sufficient movement of the spindle 18 that its limit of such movement in the door closing direction shall be substantially as depicted in Fig. 1, wherein the direction of door closing movement of the spindle is counterclockwise. The normal door closing positions of the slide block 55, the cam following roller 59 and the cam 20 are illustrated in Fig. 10. From this figure, it may be observed that with the cam thus disposed and acted upon by the forces of the springs 22 and 23 transmitted through the slide block 55, there is a positive force exerted against the cam which holds the door against its jamb. The curvature of the surface 60 of the cam is such that as the door is turned in a clockwise direction, as the mechanism is viewed in Figs. 10 and 11, the radius of the cam from its axis of rotation at the center of the spindle increases as the compression of the springs 22 and 23 increases, whereby the force against which the door must be moved to open it increases during such opening movement. Conversely the force exerted by the springs for closing the door decreases during the closing movement, so that the initial closing movement of the door tends to be rapid and gradually becomes slower. The rise 84 on the cam surface 60 near the limit of the swinging movement for opening the door not only provides increased resistance to the passage of that position, but adjoins a concavely curved portion 85 in which the roller 59 comes to rest in the fully open position of the door; in which latter position the roller acts as a spring urged detent for holding the door open.

The control mechanism for further and adjustably controlling the closing movements of a door mounted on the spindle 18 includes a piston 86 mounted for linear sliding movement in the cylinder bore 32. At the end adjacent the cam 20, the piston 86 has integrally formed thereon axially projecting fingers 87 and 88, as shown in Figs. 5 and 9, which are spaced apart and carry a cross shaft 89. Between the fingers 87 and 88, a roller 90 is rotatably supported by the cross shaft in alignment with a surface 92 of the cam, which roller serves as a cam follower. The end of the cylinder bore 32 opposite the cam 20 and roller 90 is covered by a valve plate 93. Also, the end of the piston 86 which faces the valve plate 93 has an annular and axially extending recess 94 therein, in which recess a compression spring 95 is mounted between the piston and valve plate to exert a biasing force against the piston which

holds the roller 90 in contact with the surface 92 of the cam 20.

The valve plate 93 has therein a bore 96 aligned with the cylinder bore and having an inlet check valve nipple 97 threaded into the outer end thereof. The nipple 97 has an inlet port 98 extending therethrough and preferably has a screen-type strainer 99 secured to the outer end thereof to cover the inlet bore. At its inner end, the nipple 97 provides a seat 100 for a check valve ball 102 which is movable in the bore 96 to and from engagement with the seat 100 to limit the flow through the port 98 to that from the interior of the housing 26 to the cylinder bore. The end of the compression spring 95 serves as a retainer for keeping the ball 102 in the bore 96.

At a position spaced from the bore 96, an outlet port 103 in the valve plate 93 communicates with the cylinder bore and is connected by a cross bore 104 to a needle valve chamber 105. A needle valve 106 threaded into a counterbore 107 at one end of the needle valve chamber serves to restrict the flow of liquid from the cylinder bore through the outlet port 103 and cross bore 104; the needle valve chamber 105 being in communication with the interior of the housing 26 through an outlet passage 108, an inlet valve chamber 109 and an outlet passage 110.

In substantial alignment with the axis of the piston 86, an outlet port 112 communicates with the cylinder bore 32 and is connected to the valve chamber 109 through a cross passage 113. Flow through the outlet port 112 and cross passage 113 from the cylinder bore is adjustably controlled by a needle valve 114 which is threaded into a counterbore 115 at one end of the valve chamber 109. A screw plug 116 is threaded into an opening 117 in the cover plate 16, normally to cover the adjustable needle valves 106 and 114.

In axial alignment with the outlet port 112, the piston 86 has a bore 118 and a counterbore 119, with a screw plug 120 threaded into the end of the counterbore 119 opposite the end of the piston which faces the outlet port 112. A valve needle 122 is mounted for sliding movement in the bore 118 and has a head 123 slidable in the counterbore 119 and adapted to limit the movement of the valve needle outwardly of the piston. A compression spring 124 disposed in the counterbore 119 between the head 123 on the valve needle and the screw plug 120 biases the valve needle to extended position relative to the piston. At its outer end normally projecting from the piston, the valve needle includes a tapered end portion 125 of a size to fit into the outlet port 112. A shoulder 126 on the valve needle between the projecting end portion 125 and the adjacent portion of the needle 122 serves to effect complete closure of the outlet port 112 when it engages the surface 60 of the valve plate. In my disclosed structure, the parts of the valve needle are so proportioned that when the piston is retracted, as shown in Fig. 11, the shoulder 126 is projected outwardly from the end of the piston, thereby to effect closure of the outlet port 112 during the inward movement of the piston and before the piston reaches the inner limit of its stroke.

With the parts of the control mechanism arranged as described, the piston 86 is forced into the cylinder bore with one end thereof adjacent the valve plate 93, as shown in Fig. 10, by the action of the surface 92 of the cam 20 and against the biasing force of the compression spring 95, when the mechanism is in the door closing position. When the spindle is moved to the door

opening position, as shown in Fig. 11, the roller 90 moves along the surface 92 of the cam and the compression spring 95 forces the piston outwardly of the cylinder bore to effect the flow of liquid into the cylinder bore through the inlet port 98. The operation of the piston has no practical effect upon the door opening movement of the spindle. On the other hand, however, forced movement of the piston effected by the cam against the biasing force of the spring 95 during door closing movement of the spindle 18 forces the check valve ball 102 to a closed position against the seat 100, so that the liquid entrapped within the cylinder bore must pass therefrom through the outlet ports 103 and 112 under the restrictive control of the needle valves 106 and 114 as well as the additional control provided by the valve needle 122 which is carried by the piston.

During the door closing movement, the spindle moves in a counterclockwise direction from the position of Fig. 11 to that shown in Figs. 5 and 10. In such rotation, the radius of the surface 92 with respect to the spindle axis increases, so that the tendency is to build up liquid pressure in the cylinder bore more rapidly as the piston approaches its inner limit of movement. Such action has a tendency to decrease the rate of closing movement of the door, as the door approaches its closed position. Additional to the influence in the variation of cam radius upon the rate of the spindle and door movement, the valve needle 122 which projects from the end of the piston gradually restricts the liquid flow through the outlet port 112 after a predetermined position of the piston movement is reached. The restriction of the flow through the outlet port 112 continues until it is completely closed at a position near, but not quite at the end of the inward movement of the piston. Thus, in addition to the fact that the cam contour tends to increase the liquid pressure in the cylinder bore, the outlet flow of liquid from the cylinder bore to the interior of the housing 126 is gradually restricted, to effect a definite and gradually decreasing rate of spindle movement as it approaches and reaches the door closing position.

Since the manually adjustable needle valve 114 controls the maximum rate of liquid flow through the port 112, the influence or variation of rate of door movement which is caused by the action of the valve needle 122 can be easily and definitely varied by adjustment of that needle valve. Manual adjustment of the needle valve 106 changes the relatively fixed rate of liquid outlet flow from the cylinder bore, thereby to effect control of the rate of piston movement throughout its door closing stroke and having regulating action upon the overall time and rate of the door closing movement.

As indicated in Figs. 10 and 12, the cam 20 has stop surface portions 127 and 128 which are separate from the surfaces 60 and 92 thereof and aligned for engagement with a stop post 129 which is secured at its opposite ends, as shown in Fig. 5, to the inner surface of the cover plate 16 and the supporting portion 34 of the cylinder block by fastening means, such as screws 130. Engagement of the stop surfaces 127 and 128 with the post 129 determines the maximum limits of movement of the spindle. Thus, it may be observed that peripherally separated surface por-

tions on the cam 20 coact with the cam following rollers 59 and 90 to control respectively the force acting upon the spindle and the rate of door closing movement which is effected by that force.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. In a door check mechanism, a vertical rotatable spindle to which a door is adapted to be attached, and which is adapted to be rotated by swinging movement of the door to open position, a cam on the spindle and rotatable therewith, a slide block provided with a cam follower engaging the cam, a pair of parallel rods each secured at one end of the slide block, helical compression springs on the rods urging the slide block in a direction for retaining the follower in contact with the cam and urging the cam and spindle in a door closing direction, separate adjustable abutments for the springs adjacent the ends of the rods opposite the slide block, and means comprising cooperative gears gearing the abutments together whereby adjusting movements of one of said gears for varying the compression of the spring on the respective rod effects adjustment of the other abutment for simultaneously varying the compression of the other spring.

2. In a door check mechanism, a vertical rotatable spindle to which a door is adapted to be attached and which is adapted to be rotated in one direction by swinging movement of the door toward the open position, a cam on the spindle rotatable therewith, a slide block provided with a cam follower engaging the cam, spring means urging the slide block in a direction for urging the cam and spindle toward a door closing position, threaded adjustable abutment means for the spring means adapted for adjustment in directions axially of the spring means for varying the force exerted by the cam follower against the cam, threaded means supporting the threaded abutment means, a gear on said abutment means, and a manually rotatable gear engaging said first mentioned gear and operable in directions for rotating the first mentioned gear in one direction or the other for effecting threaded axial movement of the threaded abutment member relative to said threaded supporting means for varying the compression of the spring.
